CARD PANEL

Wendell B. Ward and Stanley K. Franks, Marion, Ohio, assignors to Fulfillment Corporation of America, Marion, Ohio, a corporation of Delaware

Application December 13, 1956, Serial No. 628,128

4 Claims. (Cl. 95—85)

The present invention relates to an improved panel provided with runways for supporting card indexes in parallel relation and from which any card can be readily removed and replaced without disturbing the remaining cards.

In large engineering concerns, particularly those which entertain bids from outside contractors, for example, Government engineering departments, it is customary to provide metal panels on which detachable cards are mounted, pertaining to the details of a structure on which bids are to be solicited. These card-bearing panels are photographed for offset printing purposes and the printed material is incorporated in large loose-leaf specification or code books which are consulted by the prime contractors. When changes in design or dimensions in the structure become necessary, only that card or cards affected by the changes need be removed from the panel and substitutions made, in order that revised sheets can be printed for the specification book.

The cards are usually provided with fixing tongues cut out from both edges of the card, the tongues being inserted between the edges of a pair of parallelly disposed runways and the panel, the tongues serving detachably to clamp the ends of the cards to the panel so that the cards are arranged in horizontal parallelism down the panel and in overlapping relation to leave exposed the printed information on the upper portion of each card for photographic purposes.

The runways in the prior panels are usually formed as metal strips with upstanding edges and riveted or otherwise secured at each end to the metal panel. Metal strips of this type are difficult to make and are therefore expensive, since they involve the deformation of heavy gauge metal along both edges of the strip. This bending or upsetting of the edge requires special tools and, inasmuch as it is as long as the panel, the latter running 19" or 20" long, unless extreme precaution is taken, stresses and strains may be introduced into the strip which communicate themselves to the thin metal panel and tend to cause the panel to twist.

In accordance with one of the objects of our invention, we propose to provide an entirely new form of strip which requires no bent or upset edges, and therefore, is less expensive to make and, in addition, the strip lends itself to a new form of panel plate which is less apt to become deformed than the earlier panels.

In carrying out this object, we make the strips of flat metal and obtain the necessary spacing under the edges of the strips to accommodate the tongues of the cards by modifying the structure of the panel member.

In order to prevent the tendency of the prior panel to bend or otherwise distort on account of its considerable area (usually about 240 square inches of very thin metal), it has been the practice heretofore to provide a pair of intermediate strengthening bars, lengthwise of the panel and secured thereto at intervals. Due to their intermediate position, these bars also serve as a bottom rest or support for the cards that are arranged in overlapping relation between the runways.

2

However, in practice it has been found that these bars strengthen the central portions of the panel only in the transverse direction and would leave the remainder of the panel, both in the longitudinal and transverse directions, without any support. Consequently such panels would tend to curl, generally in the transverse direction, and the mounted cards would follow the contour of the panel and give a distorted photograph.

In accordance with another object of our invention, we eliminate the use of these bars entirely and, instead, provide corrugations formed out of the panel metal itself, these corrugations extending not only longitudinally of the panel, but also at various places across the panel over the entire length of the latter, so that the panel is reinforced not only in the transverse direction, but also in the longitudinal direction. The spacings between these corrugations are sufficiently close that there is no appreciable area of the panel which does not receive support both in the longitudinal and transverse directions from at least two or more of these corrugations. In this manner, the panel as a whole remains perfectly flat and these corrugations serve even in a more positive manner than the bars of the prior panels as a rest or support for the cards.

25 The general object of our invention is to provide an improved panel that can not only be made much less expensively than the prior panels for index cards, but also resists any tendency to curl or bend so that the index cards are inserted between the runways in a perfectly flat condition with adequate support underneath and this, in turn, produces a distortionless photograph for offset printing.

Other objects and features will be apparent as the specification is perused in connection with the accompanying drawings, in which:

Figure 1 shows a plan view of the improved panel, with cards detachably secured thereto in overlapping relation, and having a portion cut away from the cards to show the front view of the panel itself;

40 Figure 2 is a transverse sectional view of the panel taken along line 2—2 in Figure 1, but with the cards removed;

Figure 3 represents a perspective view of the improved panel and looking toward the rear at the underneath side; 45 the panel is cut away at the middle as indicated by the bracket;

Figure 4 depicts a detailed sectional view of a pair of small depressions positioned along the upper and lower edges of the panel; this view is taken along line 4—4 in 50 Figure 3;

Figure 5 is a perspective view of a corner detail of the panel, particularly showing the card clip stop provided at each end of the card-guide runways and which stop determines the uppermost and lowermost position of the 55 cards, while;

Figure 6 represents a short portion of the length of one of the index cards in order to show the character of the locking ears.

Referring to Figure 1, reference character 1 designates 60 a sheet of metal, preferably aluminum, for lightness, and having a length and width dependent upon the length of the individual cards 2 which are supported on the panel and the number of cards which it is desired to have the panel accommodate for photographic purposes.

65 As an example of the size of the panel, one that is now in use, or is contemplated for use, in a typical engineering department, is approximately 1½ ft. long by 1 ft. wide, representing 216 square inches. The thickness of a typical panel is about $\frac{1}{32}$ ". A panel of this type is used by engineering concerns for supporting a large number of cards, for example of the order of 96, the cards being approximately 11" long and 1¼" wide,

in overlapping relation, the array of cards extending down the length of the panel and held in parallel position by a pair of runways which will be described hereinafter.

These cards are placed or arranged on the panel for photographic purposes so that any printing or other indicia contained on the cards is transferred to a photographic film or plate which is later used for etching a plate in the so-called offset printing process by which pages are printed and contained in a large specification book. Contractors who compete for the work of the engineering concern have access to these books to determine the details of any product that is required, for example parts of airplanes, for which the Government is soliciting bids.

It is obvious that from time to time some of the details of the product require changes and, in order to give the bidding contractor the latest information on the structural requirements of the material or product, any individual card that is affected by the change required is withdrawn from the panel and a new card substituted, after which a new photograph of the entire panel and the assembled cards is made and reinserted in the bidding book. It is therefore necessary that some provision be made for withdrawing one or more of the cards quickly from the panel and substituting other cards which carry the changes in the structural details.

While the panel and assembled cards find their greatest utility in connection with offset printing for the purpose of preparing a book which is open to prime contractors, it is obvious that the panel and the cards can be used wherever a convenient filing system is required, and particularly where detachable cards are necessary as, for example, in a real estate broker's office where ready reference as to the available number of houses for sale or for rent and the details of each are kept and the cards may have to be replaced constantly for either new information to be applied thereon, or at the conclusion of a transaction. Many other places where panels and assembled cards can be used to advantage will readily suggest themselves to those skilled in the art.

The first card 2 of the group is usually a heading card and may, for example, have printed thereon the term "Supply Catalog," as indicated, and contain two intermediate spaced lines to effect three columns. The first column may be designated "Index Number," the middle column "Stock Number" and the third column "Description." The succeeding cards which on the drawing are designated 2a and of which there may be as many as 93, all in overlapping relation, may contain code numbers under the heading of "Index Number" and "Stock Number," referring to a code book of the engineering concern, for example, a Government contracting office. Under the heading of "Description" there may be a few word description of the article, or perhaps code number, which upon reference to the code book, will give a full description of the article or product.

A few typical numbers and descriptions have been inserted on the drawings. It will be understood that these numbers and descriptions follow directly below the column headings given on the leading card 2.

These cards are, in a typical case, approximately $1\frac{1}{4}$ " wide and perhaps 11" long, and it is essential that during the photographing operation they lie absolutely flat on the panel, supported at several intermediate positions to assure this flatness of configuration. It is also essential that the panel itself be devoid of any curl or distortion in shape, any one consideration of which may produce distortion in the photographic reproduction, and perhaps blurring or indecipherable code numbers or description appearing on the printed sheet.

Whereas, in prior panels stiffening ribs have been welded or otherwise secured lengthwise of each panel, we have found that the welding operation as applied to these ribs is not only an expensive item of manufacture,

but there is some tendency for the heat of the weld and the pressure exerted at the welding location to introduce distortion into the metal of the panel and cause the latter to curl in one or more directions.

Moreover, since these ribs are formed as items separate from the panel and welded thereto in the lengthwise direction, it is impossible to eliminate any tendency to curl or otherwise distort the panel in the transverse direction. We have discovered that by the use of corrugations which run not only longitudinally of the panel but also at spaced points across the width of the panel, the tendency to curl in the longitudinal and transverse directions of the panel is completely avoided and also the expense of providing strengthening ribs along the length of the panel and the welding operation are eliminated.

Thus, as shown on the drawings, particularly in Figure 2, longitudinal corrugations 3 are provided extending equidistantly on each side of the longitudinal metal of the panel and also transverse corrugations 4, of which usually four are provided (although only three are shown on account of the cut-away portion in Figure 1), and extending as far as possible in the transverse direction and equidistantly spaced along the length of the panel. These corrugations which represent metal drawn from the body of the panel, and therefore integral therewith, may extend for approximately $\frac{3}{32}$ " downwardly, assuming that the thickness of the panel is approximately $\frac{1}{32}$ ". It has been found that this depth of corrugation formed out of this thin metal is easily obtainable by usual pressing methods and without any substantial change in the thickness of the metal at the location of each corrugation.

In view of the close network of the corrugations, both longitudinal and transverse, effected in this manner, it has been found that all areas of the considerably sized panel, particularly those between the card runways which will be described hereinafter, are protected from distortion and since these corrugations can be formed by one and the same pressing operation, the manipulation of the panel during its manufacture is reduced to a minimum.

As a precaution against curl or distortion at the upper and lower edges of the panel, due to momentary stresses that may be set up in the metal during the corrugating process, we may provide a pair of short corrugations 5 at each edge and positioned to the right and left of the two longitudinal corrugations 3, these corrugations extending almost as far as the edge of the panel in one direction and not quite reaching the position of the first transverse corrugation.

Thus, in a panel that measures approximately 18" long and 12" wide, having a pair of longitudinal corrugations 3 located at approximately $3\frac{1}{8}$ " from center to center and 5" between each of the transverse corrugations, all of which corrugations measure approximately $\frac{1}{2}$ " wide, we have found that the small corrugations 5 need extend about $1\frac{1}{8}$ " long and have a width of approximately $\frac{1}{4}$ ", located to the right of the right-hand corrugations 3, approximately $1\frac{1}{4}$ " between centers and approximately $1\frac{1}{4}$ " from the center of the nearer transverse corrugation and the middle point of the short vertical corrugation.

These short corrugations 5 are not entirely indispensable since the longitudinal and transverse corrugations 3, 4 impart a high degree of flatness to the panel. But in order to account for any slight variations in the character of aluminum or other metal, the thickness of the metal, or in the slight variations of the corrugation-forming process, it may be, and usually is, desirable to provide the short corrugations 5 of the character described, positioned at the upper and lower edges of the panel and as seen more particularly in Figures 1 and 3.

While we do not wish to be confined to any theory as to the manner in which these short corrugations operate to compensate for the variations above mentioned,

we believe that they serve to adjust the flow of metal, particularly at the upper and lower edges of the panel when the main corrugations 3, 4 are being formed or, in other words, to supply any additional metal at the location of the ends of each corrugation demanded by the pressing outward of the panel metal when the corrugation is formed.

But whatever the correct explanation is, we have found that in certain instances, depending upon variations of thickness of metal, depth and position of the main corrugations, etc., that the short corrugation 5 in the approximate position shown and described above, is desirable, although it will be understood that our invention is not limited either to the presence or the absence of these short corrugations. It is apparent that the latter are preferably formed and provided at the same time that the main corrugations 3, 4 are formed so that no extra operation becomes necessary in this connection.

The cards 2a and the heading card 2 are arranged in parallel overlapping relation, the width of each card 2a that is exposed beyond the overlap being approximately $\frac{3}{16}$ ", sufficient to uncover the code numbers and short description within the columns indicated by the heading card for photographic purposes. In order to maintain this horizontal parallel and uniform overlapping relation, we provide guide bars which cooperate with die-cast ears on the cards, these ears being of a character as described hereinafter, to permit any one card, including the heading card, to be readily removed from its position on the panel without removing any other card, and a new card substituted with new information thereon in place of the old card as the developments or changes in design of the structure require from time to time.

Whereas in prior forms of panels it has been proposed to provide guide bars which are made of steel and have upset marginal edges, the bars being riveted or otherwise secured to the panel, we have provided a plain, flat form of bar 6 of stainless steel, i.e. without upset marginal edges and riveted, as indicated at 7, to corrugations 8 that are formed in the panel simultaneously with the corrugations 3, 4 and 5. The corrugations 8 are of smaller width than the width of the bar 6, as shown more clearly in Figure 3, so as to leave a pair of overhanging edges 9 at each side of the corrugations 8.

Thus, the bar 6 can be inexpensively made out of strip steel and the corrugation to which it is attached can be formed during the same operation as the other corrugations. It should also be noted that the corrugations 8 serve for the same purpose in strengthening a considerable area of the panel, at least in the longitudinal direction that lies between the main longitudinal corrugations 3 and the outer edges of the panel.

The cards 2 and 2a are provided with crescent-shaped cut-outs 10 (Figure 6) which leave ears 11 of a curvilinear configuration and extending upwardly and inwardly within the opening 10. The lower edge 12 of the opening 10 is spaced approximately $\frac{3}{16}$ " from the lower edge 13 of the card and this $\frac{3}{16}$ " spacing determines the width of each card that extends beyond the overlapping portions, i.e. the portion of the card that is exposed along the upper edge thereof, and showing the code numbers and short description when the cards are nested together.

In order detachably to secure each card to the panel, the ears 11 are de-pressed inwardly by the operator and caused to fit around and into the space left by the two outer overhanging ledges 9 of the bar 6, and the latter will hold the ears in a slight downwardly de-pressed position to give sufficient friction to the up and down movement of the card and thus cause the latter to maintain its overlapping or nested position with respect to the adjacent cards.

In order to remove a card from the guide bars 6, it is merely necessary to pull slightly upwardly one end of the card in order to disengage the ear from one of the overhanging edges 9, at which time the opposite ear will

disengage from the other overhanging edge. This can be done without disturbing in any substantial degree the position of the remaining nested cards.

Thus, as the specifications and other data are changed from time to time concerning a given product, of which all of the structural code numbers are set forth on the cards of each panel, the particular card which is affected by the change in code number or description can be readily removed and a new card with the changed information thereon inserted. New photographs of the entire panel with the array of up-to-date cards can then be taken to bring the specification book up-to-date. When the panel and contained cards are photographed, some reduction in size is made in order that the photograph copy will be of a size comparable to the specification book.

When the cards are assembled for the first time on the panel, the heading card 2 is first applied by bending the ears 11 and pressing them into the space left by the two outer overhanging ledges 9, and the remaining cards are applied likewise, but resting upon the next upper card but to leave exposed a space, controlled by the distance between the edges 12 and the bottom edge 13 of the card along the upper edge of the card on which each succeeding card rests. As many as ninety cards can be applied to a standard size of panel, of which the dimensions were previously given, and yet every card is readily detachable from the panel for substitution or replacement purposes.

In order to determine the position of the heading card 2 with respect to the panel, we may provide a pair of stop clips 14 which are positioned at the top of the panel, made of springy metal, and has fingers 15 at each end that fit into the space 9 left by the overhanging portion 35 of the guide bar 6. Each clip 14 is bent upwardly at the middle so as to leave a narrow space between the clip and the upper surface of the bar in order to receive the thickness of the heading card, as can be seen in Figure 1.

These clips are slideable along the guide bars 6 so as to effect any change of position of the heading card 2, but, in general, they are employed to prevent sliding the heading card up beyond the upper edges of the bars 6. Similarly, a pair of stop clips may also be provided at the lower edge of the panel in order to support the lower edges of the lowermost card 2a, since this edge does not receive any support from an overlapping card.

These cards are usually constituted of soft bendable paper, suitable for insertion in a typewriter, by which the code numbers are applied and, in order to remain in a flat state for photographic purposes, it is desirable that the upper surfaces of the corrugations 3, 4 and 5 and the bars 6 shall be at the same level.

If desired, the outer edges of the panel may also be bent inwardly, as shown at 16, and this edge also is of the same height as the bars and the corrugations so as to furnish support to the outermost ends of the cards. It is apparent that any strengthening effect in the longitudinal direction offered by the flanges 16 adds itself to that provided by the longitudinal corrugations 3 and the bars 6.

From the foregoing, it is apparent that we have disclosed a panel for index cards in which the manufacture requires, apart from the riveting of the bars 6 and the formation of the flanges 16, only one operation in providing the combined panel strengthening and card supports in one operation and the positions of the latter, together with the optional short corrugations 5, are such that the panel remains absolutely flat in both the longitudinal and transverse directions, is rugged for handling, and yet maintains the lightness of weight which is an important item where many thousands of these panels are in use or in stock in the contracting-specification departments of large engineering companies.

It will be understood that various modifications and arrangements in structure could be made without depart-

ing from the spirit of our invention and, accordingly, we desire to comprehend such modifications and substitutions of equivalents as may be considered to come within the scope of the appended claims.

Having thus fully described our invention, what we claim as new and desire to secure by Letters Patent, is:

1. A rectangular metal panel for indexing cards in position for photographic reproduction, a plurality of corrugations extending lengthwise of the panel, a plurality of corrugations extending transversely of the panel and at intermediate positions thereof whereby the panel is stiffened in the longitudinal and transverse directions by said corrugations, the longitudinal corrugations having flat top portions, a pair of bars having a planar surface and secured to the top portions of the outermost longitudinal corrugations, all of the corrugations being integral with the panel and of substantially the same thickness of metal and of the same height, said bars having widths greater than the width of the corrugations on which they rest in order to provide outer overhanging side edges, whereby the index cards can be slidably carried between the bars and guided by said outer overhanging side edges and supported by all of said corrugations.

2. A rectangular metal panel for indexing cards in position for photographic reproduction, a plurality of corrugations extending lengthwise of the panel, a plurality of corrugations extending transversely of the panel and at intermediate positions thereof whereby the panel is stiffened in the longitudinal and transverse directions by said corrugations, the longitudinal corrugations having flat top portions, a pair of bars having a planar surface and secured to the top portions of the outermost longitudinal corrugations, all of the corrugations being integral with the panel, of substantially the same thickness of metal and of the same height, said bars having widths greater than the width of the corrugations on which they rest in order to provide outer overhanging side edges, whereby the index cards can be slidably carried between the bars and guided by said outer overhanging side edges and supported by all of said corrugations, the upper surface of the bars being of substantially the same height as the corrugations in order that the latter may serve as supports for the cards.

3. A rectangular metal panel for indexing cards in position for photographic reproduction, a plurality of corrugations extending lengthwise of the panel, a plurality of corrugations extending transversely of the panel, said corrugations forming a series of rectangular networks over substantially the entire area of the panel,

5 said corrugations being integral with the panel and of substantially the same thickness, metal bars secured to upraised portions of at least two of the longitudinal corrugations, said bars being of greater width than the corrugations to which they are secured so as to leave an overhanging lip, the outermost lips of said bars being adapted to receive retaining portions of the cards in order to permit the cards to be slid along the bars to any desired position with respect to one another, the 10 longitudinal edges of the panel being bent in the same direction as the longitudinal and transverse corrugations, whereby the longitudinal corrugations and the bent-up edges serve to strengthen the panel in the longitudinal direction and the transverse corrugations serve 15 to strengthen the panel in the transverse direction.

4. A rectangular metal panel for indexing cards in position for photographic reproduction, a plurality of corrugations extending lengthwise of the panel, a plurality of corrugations extending transversely of the panel, said corrugations forming a series of rectangular networks over substantially the entire area of the panel, said corrugations being integral with the panel and of substantially the same thickness, metal bars secured to upraised portions of at least two of the longitudinal corrugations, said bars being of greater width than the corrugations to which they are secured so as to leave an overhanging lip, the outermost lips of said bars being adapted to receive retaining portions of the cards in order to permit the cards to be slid along the bars to any desired position with respect to one another, the 20 longitudinal edges of the panel being bent in the same direction as the longitudinal and transverse corrugations, whereby the longitudinal corrugations and the bent-up edges serve to strengthen the panel in the longitudinal direction and the transverse corrugations serve to strengthen the panel in the transverse direction, the height of said longitudinal and transverse corrugations, also the metal bars and the bent-up edge flanges being the same in order to furnish support for the cards that 25 are detachably mounted on the bars.
